US0D1000668S

(12) **United States Design Patent** (10) Patent No.: **US D1,000,668 S**
(45) Date of Patent: ** Oct. 3, 2023

(54) **BATTERY-OPERATED READING LAMP**

(71) Applicant: **MIOE ELEKTRONIK VE YAZILIM
MÜHENDISLIK LIMITED
SIRKETI**, Istanbul (TR)

(72) Inventor: **Umut Demirel**, Istanbul (TR)

(**) Term: **15 Years**

(21) Appl. No.: **35/515,420**

(22) Filed: **Sep. 30, 2022**

(80) **Hague Agreement Data**

Int. Filing Date: **Sep. 30, 2022**

Int. Reg. No.: **DM/224024**

Int. Reg. Date: **Sep. 30, 2022**

Int. Reg. Pub. Date: **Oct. 21, 2022**

(51) LOC (14) Cl. **26-05**

(52) U.S. Cl.

USPC **D26/61**; D26/60

(58) **Field of Classification Search**

USPC D26/24, 60, 61, 63, 73, 37

CPC F21K 9/20; F21V 21/00; F21L 4/00

See application file for complete search history.

(57) **CLAIM**

The ornamental design for a battery-operated reading lamp, as shown and described.

DESCRIPTION

1. Battery-operated reading lamp
  2. Battery-operated reading lamp
- 1.1** : Perspective
1.2 : Perspective
1.3 : Top
2.1 : Perspective
2.2 : Top
2.3 : Bottom
2.4 : Back
2.5 : Left
2.6 : Right

1 Claim, 9 Drawing Sheets
